UNITED STATES PATENT OFFICE.

KARL VÖLLER, OF DUSSELDORF, GERMANY, ASSIGNOR TO RHEINISCHE METALL-WAAREN- UND MASCHINENFABRIK, OF DUSSELDORF-DERENDORF, GERMANY, A CORPORATION OF GERMANY.

GUN WITH SLIDING BARREL.

1,209,521.

Specification of Letters Patent. Patented Dec. 19, 1916.

Application filed October 16, 1913. Serial No. 795,556.

To all whom it may concern:

Be it known that I, KARL VÖLLER, engineer, a subject of the German Emperor, residing at 12 Scharnhorststrasse, Dusseldorf, Germany, have invented certain new and useful Improvements in Guns with Sliding Barrels; and I do hereby declare the following to be a full, clear, and exact description of the invention, such as will enable others skilled in the art to which it appertains to make and use the same.

In guns having a sliding barrel the cradle, or the separate carrier for the cradle if there be such a carrier, is subjected to a severe strain by the vibrations arising both from the recoil and during travel.

This invention avoids this objection by providing the cradle or its carrier with projections on which the gun barrel is supported in its position of rest by means of claws carried by the barrel. The projections are near the bearings and preferably directly over the trunnions, so that the weight of the barrel is transmitted by the 25 projections directly to the bearings through the trunnions, and the cradle or its carrier is completely relieved of the weight when the gun is in the position of rest.

The invention is illustrated in the accompanying drawing, in which—

Figure 1 is a side elevation and Fig. 2 is a cross section.

a is the gun carriage in which the cradle carrier b is journaled by the trunnions c. The cradle d carries the guides e for the sliding barrel f. The carrier b has projections g in the same vertical plane with the trunnions c, over which claws h, forming part of the barrel, are designed to engage when the barrel is in its position of rest. In this latter position the weight of the barrel is partially transferred from the cradle to the carriage. This transposition of the weight from the cradle to the projections is rendered effective because the distance between the bearing surfaces of the

claws h and the bearing surfaces of the barrel on the guides e is somewhat less than the distance between the bearing surfaces of the projections g and the bearing surfaces of the guides e. In other words, when the gun is at rest with the claws engaging the projections g the weight is taken off of the guides e to the extent of a portion of the play between the gun and the cradle. This is shown in exaggeration in Fig. 2, the dotted line i representing the distance between the bearing surfaces of the claws h and the surface of the gun where it bears on the guide e, and the line k denoting the distance between the bearing surfaces of g and e. The projections g will not impede movement of the gun in recoiling and returning to normal position, the play between the gun and the guides e being sufficient to negative undue friction.

I claim as my invention:—

1. A gun having a sliding barrel, a cradle therefor, a pivoted member for said cradle, said barrel having a sliding movement relatively to said cradle and pivoted member, and bearings for the barrel, independent of said cradle, located adjacent to and in the same vertical plane with the pivots of said member, said bearing being designed to partially support said barrel when the latter is at rest.

2. A gun having a sliding barrel, a cradle therefor, a carrier for the cradle having trunnions, bearings for said trunnions, said carrier having projections adjacent to said trunnions, and claws extending laterally from the barrel for engaging said projections when the barrel is at rest.

In testimony whereof, I have signed this specification in the presence of two subscribing witnesses.

KARL VÖLLER. [L. S.]
